TRAVELING ADDRESSING MACHINE

Harmon P. Elliott, Watertown, Mass.

Application April 27, 1938, Serial No. 204,551

16 Claims. (Cl. 101—48)

This invention relates to addressing machines which employ printing devices or plates, as stencils, containing the address printing characters and especially printing devices having provision for the entry thereon of desired data as the dates and the amounts of orders and utilized as part of a bookkeeping system.

In certain types of businesses, as a mail order business, for instance, the address printing devices or stencils have in addition to the address printing characters a surface adapted to receive various entries and particularly the date of a customer's order and the amount of the order.

An object of the present invention is the provision of an addressing machine by which the various printing devices or stencils can be utilized conveniently to print the addresses on various departmental forms on which various parts of the total order may be subsequently entered and also to address shipping tags and the like.

A further object of the invention is the provision of a series of stencil files with an addressing machine and carriage on which the operator is mounted movable in front and lengthwise of the files to bring the addressing machine and the operator in front of any selected file so that a selected stencil thereof can be removed and utilized in the addressing machine. With this arrangement the operator can receive from a distributor a number of orders from customers whose names are contained on stencils within the files under the operative's direct control. She can then move her machine up and down the line of files and select the various stencils bearing names corresponding to the names of the orders. She places each stencil in the addressing machine and prints the address on as many order forms as are necessary, enters the appropriate parts of the total order upon the proper forms, addresses the necessary shipping labels, and enters the date and the total amount of the order upon the face of the stencil, returns the stencil to its original position in the files and moves the machine and herself along the track for the next stencil, thereby greatly facilitating and lightening her work and expediting the progress of the order through the plant. This method is also an object of the invention.

Another object of the invention is the provision of an addressing machine having an apertured guide frame that is movable into a position overlying the entry part of the printing plate and so arranged that the various entries written thereon by the operators are confined to the space allotted to the entries.

A yet further object of the invention is the provision of an improved and simplified addressing machine.

Fig. 1 is a perspective view of filing and addressing apparatus associated with the present invention.

Fig. 2 is a plan view of the traveling addressing machine.

Fig. 3 is a side elevation of the machine of Fig. 2.

Fig. 4 is a front elevation of the addressing mechanism taken along line 4—4 of Fig. 2.

Fig. 5 is a side elevation of the addressing mechanism taken along line 5—5 of Fig. 4.

Fig. 6 is a plan view of the table at the addressing position and illustrating particularly the stencil inking mechanism.

Fig. 7 is a view of the stencil inking mechanism generally similar to Fig. 4 but illustrating particularly the engaged and disengaged positions of the inking roller arm and its operating arm.

Fig. 8 is an enlarged sectional detail of the inking roller taken along line 8—8 of Fig. 7.

Fig. 9 is a plan detail of the table at the addressing position and illustrating particularly the entry guide frame.

Fig. 10 is a view similar to Fig. 9 but with the guide frame in position overlying the stencil and illustrating the manner of use of the frame.

Fig. 11 is a detail front elevation of the ink carrying roll of Fig. 4.

Fig. 12 is a detail side elevation of the roll of Fig. 11.

Fig. 13 is a sectional detail taken along line 13—13 of Fig. 11.

The addressing machine of the present invention, see Figs. 1, 2 and 3, comprises the frame structure 20 supporting a flat top table or bed 22 having the addressing elements generally indicated by the numeral 24. The frame structure 20 includes the side walls 26 and 28 and a stool 30 for the operative, the stool being connected rigidly to the frame structure by a connecting member 32. The front edge of the side wall 28 is cut away to allow easy access to the stool 30.

The addressing mechanism is operated manually by the raising and lowering of a handle 34 located outside the side wall 28.

The frame structure including the stool is provided with a series of peripherally grooved wheels 36 which roll upon parallel rails 38 located in front of and extended lengthwise of a series of file drawers or trays 40 containing a collection of printing devices as stencils, the drawers all

facing and being close to the rails and being arranged in a long row parallel with the rails.

The table 22 is provided with a box 42 containing a series of pigeon holes or compartments for various forms adapted to receive the addresses of the stencils.

The operative sitting upon the stool 30 can move herself and the carriage in either direction along the rails 38 by pushing on the floor with her feet to gain access to any desired file drawer and to remove a selected printing device therefrom without leaving the stool. She places the printing device in the addressing mechanism and makes as many printing operations as are necessary on the separate desired forms, makes an entry upon the printing device and then returns the device to its position in the file drawer.

The printing device especially adapted for use in connection with the present invention is a stencil illustrated in Figs. 9 and 10, and comprises a rectangular frame 44 having a window containing an address bearing stencil sheet 46 and a ruled surface 48 below the window adapted to receive desired data as the date and amount of an order.

The table 22 is provided with a depression 50 adjacent its front edge in which is located a pair of bars 52 having confronting grooves that constitute a support for the stencil.

The addressing mechanism includes a platen 54 located above the address bearing portion of the stencil and above the table and integral with the forward end of a vertically reciprocable platen arm 56, the rear end of which extends through an opening of the table and is fixed to a shaft 58 pivotally mounted in bearings 60 depending below the table. The arm 56 is integral with a roller arm 62 which depends below the shaft 58 and carries a roller 64 which is held in engagement with the side cam face 66 of a cam segment 68 by a spring 70. The cam segment is fixed to an oscillable shaft 72 journalled in bearings 74 depending beneath the table 22. An operating arm 76 is fixed to said shaft and extends through a slot 78, see Fig. 3, of the side wall 28 and terminates in the aforesaid handle 34. Thus by raising and lowering the handle the platen is caused to be reciprocated toward and away from the stencil therebeneath. The cam face 66 is provided with a dwell portion 80 which causes the platen to be held in its lowermost position during the printing of the address.

A printing roll 82, see also Fig. 8, is disposed beneath the stencil and platen and is adapted to be reciprocated lengthwise of and in contact with the stencil sheet of the stencil to force ink on the surface of the roll through the address characters of the stencil and onto a record sheet located above the stencil and under the platen. The roll 82 is loosely mounted on a shaft 84 and journalled in and extended through the forks 86 of an operating arm 88 and has rollers 90 on the ends of said shaft which roll on the ledges 92 of bars 94 that are L-shaped in cross-section and are secured by screws 96 to the underside of the table 22.

The ledges 92 are cross-wise of the stencil and are so located as to cause the ink roll 82 to roll on and in pressure engagement with the stencil for the greater part of the stroke of the roll. The bars 94 at one end thereof are provided with downwardly inclined slots 98 into which the shaft rollers 90 move at the end of the stroke of the roll and thereby lower the roll

away from the stencil and upon the surface of an ink drum 100.

Said ink drum 100 is fixed to a shaft 102 journalled in bearings 104 secured to the bars 94 by the aforesaid screws 96 and depending below said bars. The drum is oscillated by means including a pinion gear 106 fixed to said shaft 102 and adapted to mesh with a reciprocating rack bar 108 which is held in engagement with the pinion gear by a clip 110 which overlies the top and sides of the rack bar and is loosely pivoted on the shaft 102. The rack bar 108 is pivoted on a screw 112 fixed to the upper end of an arm 114 that is fixed at its lower end to the aforesaid shaft 72 that is reciprocated by the handle 34. Thus as the shaft is reciprocated the ink drum 100 is consequently oscillated throughout an arc sufficient to obtain proper distribution of ink on the printing roll 82, the oscillation being substantially a complete revolution.

Said rack bar is provided with a tooth-free end portion 109 which confronts the pinion gear in the unoperated position of the parts. The ink roll is thus free from positive connection with the rack and can be rotated manually by a crank handle 115 for the purpose, for instance, of distributing ink on the surface of the drum at the start of a day's work.

The operating arm 88 for the printing roll 82 is provided at its free end with a longitudinally elongated slot 116 therein which is terminated at the end confronting the printing roller in a downwardly directed notch 118. A pin or screw 120 is loosely located in said slot and is carried by the upper end of an arm 122 fixed to the aforesaid shaft 72. The arm 88 is provided with a downward extension 124 between which and the upper end of the arm 122 a tensile spring 126 is connected, the main purpose of the spring being to tend to raise the arm 88 so as to cause the pin 120 to enter the notch 118 when both are in confronting relation.

By reason of the slot 116 the ink drum 100 can be rotated in engagement with the printing roll 82 before the printing roll starts to move away from the drum on a printing stroke and hence the periphery of the printing drum is caused to be supplied with ink.

When the movement of the arm 122 is such as to enter the pin 120 thereof in the lateral notch 118 further movement of the arm 122 causes the printing roll to advance to the left and effect a printing operation. The spring 126 holds the pin in the notch 118 during reverse movement of the arm 122 thereby to return the ink roll to its initial position. In the latter part of such stationary supported movement a roller 128 disposed above the right hand end of the arm 88 is caused to come in contact with the inclined surface 130 of said arm, see Fig. 7, and to depress said arm, thereby to effect the movement of the pin 120 out of the slot 116 and thereby to disconnect the arms 88 and 122.

The ink drum 100 is supplied with ink by means of an absorbent, as felt, ink containing roll 132, see Figs. 4, 11, 12 and 13. Said roll 132 is rotatably secured between the upper ends of the arms of a U-shaped supporting frame 134 journalled loosely upon a shaft 136 and having a handle 138 by which the roller may be moved into and out of engagement with the periphery of the ink drum. The shaft has fixed thereto a bifurcated plate 140 between the furcations 142 of which is located a pin 144 fixed to one of the frame arms. An overcenter spring 146 extends

between said pin 144 and a projection 148 of the plate 140 and is so arranged as to hold the ink roll definitely either in contact with the periphery of the ink drum 100 or out of contact therewith. The shaft 136 is provided with a shoulder 150 fixed to the shaft and a non-circular extension 152 which is located in a slot 154 of a supporting arm 156 formed as a part of the bracket 104. The shaft has a clamping nut 158 screw-threaded thereon by which the shaft can be clamped rigidly and removably to the supporting arm 156. When the ink roll 132 is in need of ink the roll in its supporting frame is removed from the arm 156 by loosening the clamping nut 158 and the surface of the ink roll is passed over the face of an ink pad 160, see Fig. 3, secured to the inner face of the vertical wall 26 of the supporting structure and then replaced in position.

The addressing mechanism as thus described can be operated rapidly upon any stencil so as to print the address thereof upon as many forms as are desired.

The entry of the order or other data on the entry space 48 of the stencil is facilitated by the use of a guide frame 162, see Figs. 9 and 10. Said frame comprises a rectangular plate formed of thin sheet metal having a series of rectangular apertures 164 formed therein separated by narrow partition strips 166 which are adapted to overlie selected separating lines between vertical columns in the entry space of the stencil. Said plate 162 is provided with ears 168 which are journaled on a pin 170 carried by a bracket 172 fixed to the upper part of the platen 54. A light spring 176 encircles said pin and acts upon said plate 162 in a direction to maintain said plate in a raised or out-of-use position overlying the platen supporting arm, as illustrated in Fig. 5, but to permit said plate to be swung readily forwardly and downwardly to overlie the entry portion 48 of the stencil, as illustrated in Fig. 10, so as to enable the operative to make an entry 178 in an appropriate column of the stencil, the partition strips 166 preventing the entry from running into an adjacent column. The spring 176 automatically returns the frame to its inoperative position.

The entry 178 is or can be made with a pencil which preferably is a component part of the mechanism. As herein shown the pencil 180 is secured removably to a clip 182 fixed to the end of a flexible cord 184 which extends through a tube 186 upstanding above the table 22 and has a weight 188, see Fig. 5, at its other end located beneath the table. Thus the weight normally holds the pencil in an out-of-use position against the end of the tube 186 where it is convenient to grasp it and also restores the pencil to the same position when the operative releases her grasp thereon without the necessity for the operative to reposition the pencil.

I claim:

1. In an addressing machine, a stencil holder, a platen on one side of said holder, a printing roll on the other side of said holder, an ink drum in contact with said printing roll in the unoperated position thereof, and mechanism for imparting rotary movement to said ink drum and movement of said printing roll away from said drum and into cooperative relation with a stencil in said holder, said mechanism having a quick acting connection with said inking drum and a delayed action connection with said printing roll whereby said printing roll is caused to be inked prior to its advance toward the stencil.

2. In an addressing machine, a stencil holder, a platen on one side of said holder, a printing roll on the other side of said holder, an ink drum in contact with said printing roll in the unoperated position thereof, a reciprocatory operating mechanism, means for connecting said printing roll with said mechanism for moving said roll into and out of cooperative relation with the stencil, said mechanism including a reciprocating arm, a rack pivoted to said arm and a gear fixed to said ink drum engaged with said rack for oscillating said drum.
3. In an addressing machine, a stencil holder, a platen on one side of said holder, a printing roll on the other side of said holder, an ink drum in contact with said printing roll in the unoperated position thereof, a reciprocatory operating mechanism, means for connecting said printing roll with said mechanism for moving said roll into and out of cooperative relation with the stencil, said mechanism including a reciprocating arm, a rack pivoted to said arm and a gear fixed to said ink drum engaged with said rack for oscillating said drum, and a guide member slidably embracing said rack and having a pivotal support coaxial with said drum.
4. In an addressing machine, a stencil holder, a platen on one side of said holder, a printing roll on the other side of said holder, an ink drum in contact with said printing roll in the unoperated position thereof, a reciprocatory operating mechanism, means for connecting said printing roll with said mechanism for moving said roll into and out of cooperative relation with the stencil, said mechanism including a reciprocating arm, a rack pivoted to said arm and a gear fixed to said ink drum engaged with said rack for oscillating said drum, and means for operatively disengaging said rack and gear for permitting independent manual rotation of said drum.
5. In an addressing machine, a stencil holder, a platen on one side of said holder, a printing roll on the other side of said holder, an ink drum in contact with said printing roll in the unoperated position thereof, a reciprocatory operating mechanism, means for connecting said printing roll with said mechanism for moving said roll into and out of cooperative relation with the stencil, said mechanism including a reciprocating arm, and a rack pivoted to said arm and a gear fixed to said ink drum engaged with said rack for oscillating said drum, said rack having a tooth-free part which confronts said gear for permitting manual rotation of said drum.
6. In an addressing machine, a stencil holder, a platen on one side of said holder, a printing roll on the other side of said holder, an ink drum in contact with said roll in an unoperated position thereof, mechanism for reciprocating said roll into and out of cooperative relation with a stencil in said holder and for imparting intermittent rotational movement to said drum including a reciprocating arm, a roll carrying arm, and a lost motion connection between said arms.
7. In an addressing machine, a stencil holder, a platen on one side of said holder, a printing roll on the other side of said holder, means for guiding said printing roll for movement toward and away from a stencil in said holder and for movement cross-wise of and in contact with the stencil, an ink drum in contact with said print roll in an unoperated position thereof, reciprocating mechanism for imparting rotational movement to said ink drum and reciprocatory movement to

said printing roll only following the start of rotation of said drum, including a roll carrying arm having a longitudinally directed slot therein and a reciprocating operating arm having a part disposed in and movable lengthwise of said slot.

8. In an addressing machine, a stencil holder, a platen on one side of said holder, a printing roll on the other side of said holder, means for guiding said printing roll for movement toward and away from a stencil in said holder and for movement crosswise of and in contact with the stencil, an ink drum in contact with said print roll in an unoperated position thereof, reciprocating mechanism for imparting rotational movement to said ink drum and reciprocatory movement to said printing roll only following the start of rotation of said drum, including a roll carrying arm having a longitudinally directed slot therein and a reciprocating operating arm having a part disposed in and movable lengthwise of said slot, said slot having an offset hook extension, and means for locating said reciprocating arm releasably in said hook extension.

9. In an addressing machine, a stencil holder, a platen on one side of said holder, a printing roll on the other side of said holder, means for guiding said printing roll for movement toward and away from a stencil in said holder and for movement cross wise of and in contact with the stencil, an ink drum in contact with said print roll in an unoperated position thereof, reciprocating mechanism for imparting rotational movement to said ink drum and reciprocatory movement to said printing roll only following the start of rotation of said drum, including a roll carrying arm having a longitudinally directed slot therein and a reciprocating operating arm having a part disposed in and movable lengthwise of said slot, said slot having an offset hook extension, means for locating said reciprocating arm releasably in said hook extension, and means responsive to reciprocatory movement of said roll carrying arm for operatively disengaging said arms.

10. In an addressing machine, a stencil holder, a platen on one side of said holder, a printing roll on the other side of said holder, an ink drum engageable with said printing roll to apply ink thereto, a reciprocatory operating member for said printing roll, means connecting said arm and roll for moving said roll into and out of cooperative relation with a stencil in said holder, means including said ink drum limiting movement of said printing roll in one direction, and means forming a part of said connection between said printing roll and reciprocating member for permitting further movement of said reciprocating member in the same direction.

11. In an addressing machine, a stencil holder, a platen on one side of said holder, a printing roll on the other side of said holder, a guideway along which said printing roll is reciprocable, a reciprocating operating arm, a roll carrying arm having a releasable latch connection with said

reciprocating arm, means responsive to a movement of said roll carrying arm in one direction for disengaging said latch connection, and means responsive to movement of said reciprocating arm in the opposite direction for effecting engagement of said latch connection.

12. In an addressing machine the combination of a holder for a record receiving stencil, printing elements operative upon the stencil, and an apertured guide member arranged to overlie the record-receiving part of the stencil when the stencil is in cooperative relation with the printing elements, the apertures constituting means defining the record-receiving surfaces of the stencil.

13. In an addressing machine the combination of a holder for a record receiving stencil, printing elements operative upon the stencil, and an apertured guide member arranged to overlie the record-receiving part of the stencil, when the stencil is in cooperative relation with the printing elements, the apertures constituting means defining the record-receiving surfaces of the stencil, said member having means for supporting it for movement into and away from stencil confronting position.

14. In an addressing machine the combination of a holder for a record receiving stencil, printing elements operative upon the stencil, and an apertured guide member arranged to overlie the record-receiving part of the stencil when the stencil is in cooperative relation with the printing elements, the apertures constituting means defining the record-receiving surfaces of the stencil, said member having means for supporting it for movement into and away from stencil confronting position, and means biasing said member for movement away from the stencil.

15. In an addressing machine the combination of a holder for a record receiving stencil, printing elements movable toward and away from the stencil on opposite sides thereof, an aperture guide plate carried by one of said printing elements when the stencil is in cooperative relation with the printing elements and movable therewith and arranged to overlie the record receiving part of the stencil, the apertures of said guide plate constituting means defining the record-receiving surfaces of the stencil.

16. In an addressing machine the combination of a holder for a record receiving stencil, printing elements movable toward and away from the stencil on opposite sides thereof, an apertured guide plate carried by one of said printing elements when the stencil is in cooperative relation with the printing element and movable therewith and arranged to overlie the record receiving part of the stencil, the apertures of said guide plate constituting means defining the record-receiving surfaces of the stencil, and means biasing said plate for movement on the aforesaid printing element for movement away from the stencil.

HARMON P. ELLIOTT.
